UNITED STATES PATENT OFFICE.

WINFIELD HANCOCK YOST, OF MONTREAL, QUEBEC, CANADA.

SHAFT-ROTATING MEANS.

1,239,551.

Specification of Letters Patent. Patented Sept. 11, 1917.

Application filed December 9, 1912. Serial No. 735,798.

To all whom it may concern:

Be it known that I, WINFIELD HANCOCK Yost, a citizen of the United States, residing at Montreal, Province of Quebec, Canada, have invented certain new and useful Improvements in Shaft-Rotating Means; and I do hereby declare that the following is a full, clear, and exact description of the same.

- 10 This invention relates to shaft rotating means of the type in which rotation of the shaft is effected by an oscillating or reciprocating device adapted to alternately engage with and disengage therefrom, and further 15 to manually operated devices of the above type in which the manually operated member is adapted to remain out of operative relation with, and adjacent to the shaft when the device is not in operation.
- 20 The invention has for an object to provide a simple and easily adjusted and operated device of this type whereby the shaft may be rotated in either direction as desired.

25 Figure 1 is a plan view of the device, the shaft to which it is applied being shown in transverse section.

Fig. 2 is a side elevation thereof.

Fig. 3 is a vertical section on the line 3—3

30 Fig. 1.

Figs. 4 and 5 are perspective views respectively of the saddle carrying the lever and the arm on which it is mounted.

The shaft to be rotated is shown at 1 and 35 may be employed as the brake mast of a car, a door operating shaft or applied to other purposes.

Secured upon the shaft by suitable means as the key 2 is an equal faced ratchet wheel, 40 or star wheel, 3 which may be further secured to the shaft by means of a bolt 4 passing through the elongated hub of the ratchet wheel. This ratchet wheel is adapted

45 to be engaged and operated to rotate the shaft by a reciprocating or oscillating lever or handle 5 fulcrumed between its ends in a manner to be presently pointed out, the portion thereof between the fulcrum and ratchet wheel comprising a reversible double faced 50 pawl 6.

This lever 5 is carried upon a bracket arm or carrier pivoted at one end upon the shaft, this carrier as here shown being formed by

a two piece strap 7 loosely encircling the elongated hub 8 of the ratchet wheel, a 55 flange 9 on the hub preventing longitudinal displacement of the carrier.

In operation the lever is adapted to alternately engage with and disengage from the ratchet as it is moved back and forth 60 and rotate the shaft step by step, the lever being mounted by means of a universal joint in a manner both to have lost motion between itself and the carrier, to cause it to engage and disengage upon reciprocating, 65 and also to permit of the shifting thereof to reverse the position of the pawl with respect to the ratchet wheel to enable the ratchet wheel to be rotated in either direction as desired, the position of the lever 70 when the shaft is being rotated in different directions being indicated respectively by the full lines and chain lines in Fig. 1.

As here shown a saddle 15 is mounted on the end of the carrier 7 by means of a bolt 16 passing through registering perforations 17 and 18 in the carrier ends and saddle respectively, the saddle straddling the end of the carrier and being pivoted to swing in a plane common to the axis of the shaft. 75 Projecting upwardly from the saddle and integral therewith is a hollow boss 19 upon which the lever is fulcrumed on an axis parallel to the shaft axis, the lever being retained in position upon the boss by means 80 of the bolt 20 with the nut and washer 21 thereon.

To limit the lost motion between the lever and carrier to that necessary to cause the pawl to clear the ratchet wheel a lug 22 is 90 formed on the lever and engages the front of the saddle when the pawl has cleared the ratchet wheel, which lug may be duplicated as shown so that the lever may be placed in position with either side thereof turned toward the saddle.

In operation the lever is swung upon its universal joint until it engages the ratchet wheel, the engagement of the saddle 15 with the upper face of the carrier limiting the 100 movement of the lever on the bolt 16 when it is in line with the ratchet wheel. The lever is then reciprocated and alternately engages with and rotates the ratchet and 105 disengages and moves back independently of the ratchet, the lever first swinging on the

boss 19 until the lug 22 bears against the saddle and causes the lever and carrier to swing together on the shaft.

If the direction of rotation of the shaft 5 is to be changed it is only necessary to swing the lever on the bolt 16 until it clears the ratchet when it may be shifted from one position to the other as will be readily seen from the chain line position of the lever in 10 Fig. 1 the lug 22 assumes the proper position with respect to the saddle to permit the limited lost motion when the lever is in either position.

When not in use the lever hangs alongside 15 the shaft as shown in dotted lines in Fig. 2.

It will be noted that the saddle 15 in addition to its function as a member of the universal joint, also serves to brace the ends of the strap forming the carrier.

20 What I claim is as follows:

1. The combination with a shaft, of a ratchet wheel fixed thereon, an arm pivoted concentrically thereto, a saddle pivoted upon and straddling the end of said arm, and a 25 lever fulcrumed between its ends upon such arm, such lever having one end constituting a reversible pawl adapted to engage and rotate the said ratchet wheel in either direction and means providing a universal joint 30 connection between such lever and arm, such means including a saddle pivoted upon and straddling the end of the said arm and having the lever pivoted thereto, for the purpose set forth.

35 2. The combination with a shaft and a toothed wheel upon the shaft, of an arm pivoted at one end concentrically to such shaft and a lever adapted to engage the wheel and rotate the shaft in either direction, the lever 40 being pivoted to the arm, the pivotal connection between lever and arm comprising two angularly disposed axes whereby the lever is permitted two swinging and operative movements independently of the arm 45 and in two distinct directions with relation to such arm.

50 3. The combination with a shaft, of a carrier and a lever supported by said carrier and adapted to rotate the shaft in either direction, such lever having a swinging movement transversely of the shaft and inde-

pendently of the carrier and a swinging movement in the longitudinal line of the shaft and independently of the carrier.

4. The combination with a shaft, of a 55 carrier and a lever supported by said carrier and adapted to rotate the shaft in either direction, such lever having a horizontal swinging movement independently of the carrier and a vertical swinging movement 60 independently of the carrier.

5. The combination with a shaft, of a ratchet wheel fixed thereon, an arm pivoted concentrically thereto, a saddle pivoted on the free end of the arm, and a lever fulcrumed between its ends upon the saddle and adapted to engage and rotate the said ratchet wheel in either direction and move upon its fulcrum into and out of engagement with the ratchet wheel such lever having a projection adapted to engage the said saddle and limit the movement of the lever upon its fulcrum in one direction, for the purpose set forth.

6. The combination with a shaft, of a 75 ratchet wheel fixed on the shaft, an arm pivoted concentrically thereto, a lever adapted to engage with and rotate said ratchet wheel in either direction and projections on opposite surfaces of the lever, such lever being 80 adapted to be pivoted to the arm with either of said surfaces adjacent thereto and with one of said projections in position to engage with such arm.

7. The combination with a shaft, of a 85 ratchet wheel fixed thereon, an arm pivoted concentrically to the shaft, a pivot carried by said arm and disposed transversely to the shaft, a member mounted upon said pivot to turn thereon, a second pivot carried by 90 said member and disposed substantially parallel to the shaft and a lever mounted upon the second pivot to turn thereon, such lever being adapted to engage and rotate said ratchet wheel in either direction.

95 In testimony whereof, I have signed my name to this specification, in the presence of two subscribing witnesses.

WINFIELD HANCOCK YOST.
